US0D1013281S

(12) **United States Design Patent** (10) Patent No.: **US D1,013,281 S**
(45) Date of Patent: ** Jan. 30, 2024

(54) **PROTECTIVE FACE MASK**

(71) Applicant: **Yuansheng Yan**, Bayan Nur (CN)

(72) Inventor: **Yuansheng Yan**, Bayan Nur (CN)

(**) Term: **15 Years**

(21) Appl. No.: **35/515,917**

(22) Filed: **Dec. 5, 2022**

(80) **Hague Agreement Data**

Int. Filing Date: **Dec. 5, 2022**

Int. Reg. No.: **DM/225715**

Int. Reg. Date: **Dec. 5, 2022**

Int. Reg. Pub. Date: **Dec. 30, 2022**

Assistant Examiner — Justin A Johnson

(57) **CLAIM**

The ornamental design for a protective face mask, as shown and described.

DESCRIPTION

1. Protective face mask

1.1 : Front

1.2 : Back

1.3 : Left

1.4 : Right

1.5 : Top

1.6 : Bottom

1.7 : Front perspective view

1.8 : Back perspective view

The broken lines shown in the drawings depict portions of the protective face mask that form no part of the claimed design; the front panel of the protective face mask is transparent.

1 Claim, 8 Drawing Sheets
